DESIGN FOR A DUPLICATING MACHINE

Leo R. Randell, Chicago, Ill., assignor to Ditto,
Incorporated, Chicago, Ill., a corporation of
West Virginia

Application February 2, 1946, Serial No. 126,219

Term of patent 14 years

(Cl. D64—11)

To all whom it may concern:

Be it known, that I, Leo R. Randell, a citizen of the United States and a resident of Chicago, in the county of Cook and State of Illinois, have invented a certain new, original, and ornamental Design for a Duplicating Machine, of which the following is a specification, reference being had to the accompanying drawing, forming part thereof, in which,

Fig. 1 is a front perspective view of a duplicating machine showing the essential features of my new design in full lines; and

Fig. 2 is a rear elevation thereof.

I claim:

The ornamental design for a duplicating machine, as shown and described.

LEO R. RANDELL,
